(57) **CLAIM**

The ornamental design for a bumper mountable tire carrier, substantially as shown and described.

DESCRIPTION

FIG. 1 is a left side perspective view of a bumper mounted tire carrier, showing the present invention.

FIG. 2 is an enlarged right side perspective view of a portion thereof.

FIG. 3 is a front perspective view thereof.

FIG. 4 is a left, rear perspective view thereof; and,

FIG. 5 is a left, front perspective view thereof.

The broken lines illustrate portions of the bumper mountable tire carrier which form no part of the claimed design.

The dash-dot broken lines in FIGS. 1 and 2 illustrate a boundary line of the enlarged view, and form no part of the claimed design.

Welding artifacts and irregularities form no portion of the claimed design.

1 Claim, 5 Drawing Sheets

FIG. 1

FIG. 2

FIG. 3

FIG. 4

FIG. 5
